(57) **CLAIM**

The ornamental design for a bag, as shown and described.

DESCRIPTION

FIG. 1 is a top, front and right side perspective view of a bag, showing the new design wherein the front and rear sides are the same;

FIG. 2 is a right side elevation view thereof;

FIG. 3 is a left side elevation view thereof;

FIG. 4 is a top plan rear elevation view thereof;

FIG. 5 is a bottom plan view thereof; and,
FIG. 6 is a bottom perspective view thereof showing the bag in a folded condition.
